UNITED STATES PATENT OFFICE.

EDWIN A. GRUSHUS, OF MIDAS, NEVADA.

CARBURETER.

1,248,105.

Specification of Letters Patent. Patented Nov. 27, 1917.

Application filed September 20, 1916. Serial No. 121,219.

To all whom it may concern:

Be it known that I, EDWIN A. GRUSHUS, a citizen of the United States, residing at Midas, in the county of Elko and State of Nevada, have invented certain new and useful Improvements in Carbureters, of which the following is a specification.

My invention relates to new and useful improvements in carbureters, the primary object of my invention being the provision of a carbureter in which the liquid fuel is taken up by the air entering the carbureter because of passage of such air through a fabric mantle partially immersed in the liquid fuel and acting as a wick.

A further object of my invention consists in the provision of a carbureter having a novel type of compound valve structure including a valve seat and superimposed valve disks, one of which forms what may be termed a proportionating disk or valve and the other a throttle disk or valve.

In this connection, another object which I have in view is the arrangement of ports or passages in the valve seat and valves in such a manner that the ordinary running of the engine may be controlled wholly by adjustment of the throttle valve disk and the proportionating valve disk need be employed only as a means for varying the richness of the mixture to adapt it to climatic changes and the like.

A still further object of my invention resides in the construction of a carbureter embodying the above mentioned features in a simple and durable manner, the body or casing of the carbureter being formed in sections which may be readily assembled and which may be easily separated when it is necessary to clean the carbureter.

With these and other objects in view, my invention will be more fully described, illustrated in the accompanying drawings, and then specifically pointed out in the claims which are attached to and form a part of this application.

In the drawings:

Figure 1 is a perspective view of a carbureter constructed in accordance with my invention;

Fig. 2 is a top plan view of the carbureter;

Fig. 3 is a central vertical sectional view taken on the line 3—3 of Fig. 2;

Fig. 4 is a plan view of the valve seat forming disk;

Fig. 5 is a corresponding view of the proportionating valve disk;

Fig. 6 is a similar view of the throttle valve disk.

Corresponding and like parts are referred to in the following description and indicated in all the views of the drawings by the same reference characters.

The body or casing of my improved carbureter consists of three chief sections 10, 11 and 12, the intermediate or main body section 10 being preferably substantially cylindrical in shape, open at its upper end and closed at its lower end by a bottom wall 13. This intermediate section constitutes the float chamber of the carbureter and is formed at its upper end with a radially projecting upwardly curved extension 14 providing an air inlet passage 15. This extension has its side walls projecting substantially tangentially to diametrically opposed portions of the wall of the chamber 10 and converging outwardly toward each other to extend substantially tangentially to the upwardly directed cylindrical air inlet branch 15 to which may be attached a hot air pipe, if desired. Because of this shaping of the air inlet passage 15, air entering the upper portion of the float chamber passes completely across it.

The bottom wall 13 of the float chamber is formed centrally with a depending internally threaded nipple 17 to receive a plug, indicated as a whole by the numeral 18 which forms both the valve seat and a means for attachment for the lower portion 12 of the casing, as will be later explained. This plug 18 has a reduced upper terminal which is threaded into the nipple 17 and is formed centrally of its lower face with a threaded socket 19 which is intersected at its inner portion by a plurality of radially extending diametrically disposed slots 20 opening through the sides of the plug. Beyond the inner end of this socket, the plug is formed with a central passage 21 which extends but a slight distance and which opens into a plurality of upwardly diverging branch passages 22 opening through the upper end of the plug and circumferentially disposed with respect to the main passage 21. This main passage 21 is further provided with a reduced extension 23 through which projects the stem or push rod 24 of the float 25. This float 25 is preferably constructed in the form of an annulus, being made of sheet metal in

the usual manner and provided with a closed bottom 26 whereby a cylindrical well is formed centrally of the float to which fuel is admitted through the passages 27. The valve stem or push rod 24 is secured to the central portion of this bottom and is free for sliding movement in the reduced bore 23 of the plug 18.

Pivotedly mounted in the slots 20, of which there are preferably four, are the valve levers 28 counterweighted at their outer ends, as shown at 29 and having reduced inner ends 30 which constantly engage a ball valve 31 which cooperates with the lower end of the passage 21 to control the flow of fuel into the float chamber. Obviously when the fuel level in the float chamber reaches a predetermined point, the push rod 24 will be elevated to permit the weighted ends of the levers to swing downwardly and to lift the ball valve 31 to close the passage 21.

The lower body or casing member 12 is in the form of a cup, the upper edge of which is provided with an annular seat 32 to receive the lower end of the intermediate body section 10. This cup, at its bottom, is formed with an opening 33 and a nut 34 passed through this opening and into the threaded end of the plug 18 serves as a means for securing the body section 12 to the section 10. This cup shaped body section, at its lower portion, is formed with a radially extending fuel inlet branch or pipe 35 threaded at its end in order that a fuel supply pipe 36 may be connected to it by a suitable coupling 37.

A valve seat forming disk 38 rests upon the upper open end of the intermediate body section 10 and the upper body section 11, which is in the shape of an inverted cup, and has its edge formed with an annular seat 38' so proportioned as to receive the peripheral edge of the disk 38 and to provide a depending flange 39 which will encircle the upper portion of the intermediate body section 10 in order that the upper and intermediate body sections and disk may be held in proper alignment with each other. A pin 40, projecting from the upper edge of the body section 10, passes through a notch 41 formed in the peripheral edge of the disk 38 and into a socket 42 formed in the lower edge of the section 11 to hold the parts, particularly the disk, against turning movement. The wall of the intermediate body section 10, adjacent its upper end, is provided with vertically formed bosses 43 having threaded sockets to receive clamping bolts 44 which are passed through radially projecting ears 45 formed upon the lower edge portion of the upper body section 11. This upper body section, at one side, preferably the side opposite the air inlet passage 15, is provided with a mixture outlet pas-

sage 46 which is preferably circular in cross section and which extends vertically from the carburetor proper, being at least equal in cross sectional area to the cross sectional area of the air inlet passage 15. The extension providing this passage 46 is formed at its free end with a substantially elliptical flange 47 having threaded bores 48 in order that the carburetor may be bolted to the corresponding flange of an inlet manifold.

The valve seat forming disk 38 is provided on its under face with an annular depending and outwardly projecting rib or flange 49 and a conical shaped frame 50 of relatively stiff foraminous material, such as wire gauze or netting, has its edge bent inwardly over the flared lower edge of the flange. In like manner, a conical mantle 51 of cloth or other suitable material has its edge passed inwardly about the flange, the frame and mantle being supported in this position by a split resilient clamping ring 52 which engages about the edge portions of the frame and mantle and which seats between the flange 49 and the disk. The frame 50 serves to hold the mantle 51 in extended position and the frame and mantle are so proportioned that their apex portions project somewhat below the fuel level in the float chamber.

The disk 38 is thickened centrally in order that a cylindrical bearing socket 53 may be formed in its upper face to receive the lower end of the stem 54 of a proportionating valve disk 55 which is fixed to its stem and which rests upon the upper face of the valve seat forming disk 38. A throttle valve forming disk 56 seats upon the upper face of the proportionating valve disk and is formed centrally with a sleeve 57 which surrounds the stem 54, both the sleeve and stem projecting through the upper wall of the upper body section 11 of the carburetor with the stem projecting somewhat beyond the free end of the sleeve. Valve levers 58 and 59 are secured to the outer or free ends of the valve stem and valve sleeve, respectively, and at their ends are apertured, as shown at 60, in order that they may be connected to suitable controlling links or levers so that the valves may be properly controlled from the steering wheel or dash of the vehicle. A helical spring 61 surrounds the valve sleeve 57, engaging at one end against the inner face of the body section 11 and at its other end against the upper face of the throttle valve disk 56 to hold the disks in close frictional engagement with each other.

As best shown in Figs. 4 to 6 of the drawings, the valve disk 38 is provided with a pair of oppositely formed quarter annulus shaped air ports *a*, the valve disk 55 with a similar pair of air ports *b*, and the valve

disk 56 with a similar pair of air ports *c*. Also, the valve disk 38 is formed with a quarter annulus shaped fuel port *d* of considerably lesser width than the air ports and 5 having a lesser radius of curvature, this port being located in one of the quadrants of the disk between the air ports. The valve disk 55 is formed with a similar fuel port *e* which is, however, located in the same quadrant with one of the air ports. The valve disk 56 is also formed with a fuel port *f* located in one of the quadrants lying between the air ports and substantially quarter annulus shaped, the sole difference being 10 that this port tapers uniformly somewhat from one end to the other. As shown in Fig. 3, these various ports are so formed in the valve disks that the fuel ports open within the mantle supporting cage 50, while 15 the air ports open into the float chamber outside of this cage.

First considering merely the valve disks 38 and 55, it will be noted that if the latter is superimposed upon the former in the relative angular positions which they occupy in 20 Figs. 4 and 6, the fuel ports *d* and *e* will be in absolute registration, while the air ports *a* of the disk 38 will be lapped by the disk 55 and the air ports *b* of the disk 55 will be 25 lapped by the disk 38. By turning the disk 55 in a clockwise direction, the passage through the aligned fuel ports will be diminished in length, while passages, gradually increasing in length, will be formed by 30 the partially registering air ports *a* and *b*. In normal running position of the carbureter, the portion indicated at *m* will be located at substantially the position indicated at *n* on the disk 38. Under these 35 conditions, the fuel passage provided will, in length, be only equal to substantially one-third of the length of the fuel passages of the disks, while the air passages provided will equal in length about two-thirds of the 40 length of the air passages of the disks. Assuming that the valve disk 56 is then applied in the relative angular position shown in Fig. 5, it will be clear that the fuel and both of the air passages will be completely closed. 45 If, however, this valve disk 56 is turned in a 50 counterclockwise direction, both of the air passages and also the fuel passage will begin to open, the extent of their opening being dependent upon the degree through which 55 the disk 56 is turned. Inasmuch as the fuel passage of the disk 56 increases in width from that end first overlying the open portion of the fuel passages through the other disks, it will be clear that the fuel passage 60 as a whole not only increases in length until the entire length of such passage open through the disks 38 and 55 is exposed, but further increases in size, due to an increase in width upon further turning of the disk 65 56. Because of this, the proportion of fuel

and air supplied to the mixing chamber above the valves is kept uniform for all opening of the valves. The valve disk 56 constitutes the throttle valve of the carbureter and governs the amount of explosive 70 mixture furnished to the engine. This mixture may be weakened by turning the proportionating valve disk 55 in a clockwise direction or enriched by turning such disk in a counterclockwise direction as such movements of the disk 55 will decrease or increase the size of the opening formed by the overlapping portions of the fuel passages *d* and *e*.

In operation, any suitable liquid fuel, 80 such as gasoline, is admitted to the lower casing section *f* and passes the ball valve 31 which is held in depressed position by the push rod 24 of the float and so enters the float chamber until the float has been 85 raised sufficiently to permit closing of the ball valve 31 under the action of its weighted levers 29 when further supply of fuel to the float chamber will, of course, be cut off. Assuming that the valve disks 38 and 55 are 90 set in normal running position, as previously explained, and that the valve disk 56 is so set as to close all passages through the valves, the operator will turn the throttle valve disk in a counterclockwise direction 95 through a relatively small angle to slightly open both the fuel and air passages. The engine may then be started in the usual manner, after which the throttle valve disk may be further turned in one direction or another to increase or decrease the speed of the engine at will. The lower end of the cloth or fabric mantle 51 being immersed in the liquid fuel becomes saturated with such fuel and the fuel is drawn up to completely 100 saturate the entire mantle by capillary attraction. Under these conditions, the air drawn by the engine cylinders in the carbureter through the passage 15 is drawn partially to the mixing chamber above the valves through the air passages and partially through the mantle and the fuel passages. That portion of the air drawn through the mantle takes up liquid fuel 105 from the mantle in the form of a very fine vapor and this mixed air and vapor, which would be too rich to provide a suitable explosive mixture, enters the mixing chamber and is there commingled with the air entering through the air passages and which has taken up little, if any, fuel from the wick to provide a proper explosive mixture.

All air passing through the mantle, irrespective of the rate of speed of its passage, 115 will take up liquid fuel in the form of a very fine vapor so that a good explosive mixture is insured at all speeds of the engine and no adjustments of the carbureter, save those necessitated by climatic changes 120 and like causes, are necessary.

Obviously, various changes in construction may be made without in the slightest degree departing from the spirit of my invention and I, therefore, reserve the right 5 to make any alterations which may fall within the scope of the appended claims.

Having thus described the invention, what is claimed as new is:

1. In a carbureter, a float chamber, a 10 mixing chamber, means in the float chamber for holding fuel in suspension, means for admitting air to the float chamber, and means controlling the passage of air from the float chamber to the mixing chamber, 15 said means permitting direct passage of part of the air to the mixing chamber and causing the remainder of the air to pass through the fuel suspending means before its admission to the mixing chamber.

20 2. In a carbureter, a float chamber, a mixing chamber, means in the float chamber for holding fuel in suspension, means for admitting air to the float chamber, and means controlling the passage of air from 25 the float chamber to the mixing chamber, said means permitting direct passage of part of the air to the mixing chamber, causing the remainder of the air to pass through the fuel suspending means before 30 its admission to the mixing chamber and being adjustable to vary the combined amount of air so admitted.

3. In a carbureter, a float chamber, a 35 mixing chamber, means in the float chamber for holding fuel in suspension, means for admitting air to the float chamber, and means controlling the passage of air from the float chamber to the mixing chamber, said means permitting direct passage of 40 part of the air to the mixing chamber, causing the remainder of the air to pass through the fuel suspending means before its admission to the mixing chamber and being adjustable to vary the proportions of 45 air directly admitted and of air admitted through the fuel suspending means.

4. In a carbureter, a float chamber, a 50 mixing chamber, means in the float chamber for holding fuel in suspension, means 55 for admitting air to the float chamber, and means controlling the passage of air from the float chamber to the mixing chamber, said means permitting direct passage of part of the air to the mixing chamber, causing the remainder of the air to pass 60 through the fuel suspending means before its admission to the mixing chamber and being adjustable to vary the proportions of air directly admitted and of air admitted 65 through the fuel suspending means and further adjustable to limit the total amount of air admitted to the mixing chamber.

5. In a carbureter, a float chamber, a 65 mixing chamber, a ported valve seat separating the two, means for admitting air to the

float chamber, means within the float chamber for holding fuel in suspension, and valves coöperating with each other and with the valve seat governing the amount of air admitted from the float chamber to the 70 mixing chamber.

6. In a carbureter, a float chamber, a mixing chamber, a ported valve seat separating the two, means for admitting air to the float chamber, means within the float 75 chamber for holding fuel in suspension, and valves coöperating with each other and with the valve seat governing the passage of air to the mixing chamber whereby a portion of the air passes directly to the 80 mixing chamber and the remainder passes to the mixing chamber through the fuel suspending means.

7. In a carbureter, a float chamber, a 85 mixing chamber, a ported valve seat separating the two, means for admitting air to the float chamber, an absorbent body adapted to project partially into the fuel contained in the float chamber and surrounding one of the ports in the valve seat 90 whereby a portion of the air passage to the mixing chamber will be drawn through the absorbent body, and means governing the passage of air through the ports of the 95 valve seat.

8. In a carbureter, a float chamber, a mixing chamber, a ported valve seat separating the two, means for admitting air to the float chamber, an absorbent body adapted to project partially into the fuel 100 contained in the float chamber and surrounding one of the ports in the valve seat whereby a portion of the air passing to the mixing chamber will be drawn through the absorbent body, and means governing 105 the passage of air through the ports of the valve seat, said means including a proportionating valve coöperating with the ported valve seat to fix the proportions of air passing directly from the float chamber to 110 the mixing chamber and passing from the float chamber through the absorbent body to the mixing chamber.

9. In a carbureter, a float chamber, a 115 mixing chamber, a ported valve seat separating the two, means for admitting air to the float chamber, an absorbent body adapted to project partially into the fuel contained in the float chamber and surrounding one of the ports in the valve seat 120 whereby a portion of the air passing to the mixing chamber will be drawn through the absorbent body, and means governing the passage of air through the ports of the valve seat, said means including a proportionating valve coöperating with the ported valve seat to fix the proportions of air passing directly from the float chamber to 125 the mixing chamber and passing from the float chamber through the absorbent body 130

to the mixing chamber, and a throttle valve for controlling the total amount of air passing from the float chamber to the mixing chamber.

5 10. In a carbureter, a float chamber, a mixing chamber, a ported valve seat separating the two, means for admitting air to the float chamber, an absorbent body adapted to project partially into the fuel contained in the 0 float chamber and surrounding one of the ports in the valve seat whereby a portion of the air passing to the mixing chamber will be drawn through the absorbent body, and means governing the passage of air through 5 the ports of the valve seat, said means including a proportionating valve coöperating with the ported valve seat to fix the proportions of air passing directly from the float chamber to the mixing chamber and passing 0 from the float chamber through the absorbent body to the mixing chamber, and a throttle valve for controlling the total amount of air passing from the float chamber to the mixing chamber, said throttle 5 valve being arranged to increase the proportion of the amount of air passing through the absorbent body to the amount of air passing directly to the mixing chamber upon increase of the total amount of air passing 0 from one chamber to the other.

11. In a carbureter, a float chamber having an air inlet, a mixing chamber, a valve seat cutting off communication between the two and provided with a fuel port and an air port, a valve disk resting upon the valve seat and provided with corresponding fuel and air ports capable of being brought into more or less complete registration with the corresponding ports of the seat, a second 0 valve disk engaging the first valve disk and provided with fuel and air ports capable of being brought into more or less complete registration with the corresponding ports of the first valve disk, and an absorbent 5 body supported by the valve seat and adapted to project partially below the surface of the fuel in the float chamber and so disposed that air drawn through it will pass through the aligned fuel ports of the valve seat and 0 disks.

12. In a carbureter, a float chamber, a mixing chamber, means for supplying air to the float chamber, a valve seat having a fuel port and an air port separating the chambers, a flange depending from the valve seat, a conical mantle of absorbent material secured to the flange with its smaller end depending below the fuel level of the float chamber, that end of the mantle engaging 5 the flange inclosing the fuel port of the valve seat, and means coöperating with the valve

seat for controlling the passage of air to the mixing chamber.

13. In a carbureter, a float chamber, a mixing chamber, means for supplying air to the 65 float chamber, a valve seat having a fuel port and an air port separating the chambers, a flange depending from the valve seat, a conical mantle of absorbent material secured to the flange with its smaller end depending below the fuel level of the float chamber, that end of the mantle engaging the flange inclosing the fuel port of the valve seat, and means coöperating with the valve seat for controlling the passage of air to the 75 mixing chamber, said means including a proportionating valve governing the proportion of air which shall pass through the fuel passage with respect to the proportion of air which shall pass through the air passage.

14. In a carbureter, a float chamber, a mixing chamber, means for supplying air to the float chamber, a valve seat having a fuel port and an air port separating the chambers, a flange depending from the valve seat, a conical mantle of absorbent material secured to the flange with its smaller end depending below the fuel level of the float chamber, that end of the mantle engaging 80 the flange inclosing the fuel port of the valve seat, and means coöperating with the valve seat for controlling the passage of air to the mixing chamber, said means including a proportionating valve governing 85 the proportion of air which shall pass through the fuel passage with respect to the proportion of air which shall pass through the air passage, and a throttle valve controlling the total amount of air which 90 shall pass.

15. In a carbureter, an intermediate fuel chamber forming body section closed at its lower end and open at its upper end, a fuel valve cage engaging through the closed end 105 of the body member, a lower fuel inlet body member formed with a seat to receive the intermediate body member, securing means passed through the lower body member and engaging the valve cage to lock the body 110 members together, means for admitting air to the fuel chamber to take up fuel therein, a valve seat closing the upper end of the intermediate body member providing passage for fuel and air, and an upper body 115 member forming a mixing chamber engaging the periphery of the valve seat and formed with a flange encircling the upper edge of the intermediate body member.

In testimony whereof I affix my signature. 120

EDWIN A. GRUSHUS. [L.S.]
